UNITED STATES PATENT OFFICE.

CHARLES E. MICKLEY, OF YORK, PENNSYLVANIA, ASSIGNOR OF ONE-HALF
TO WALTER F. MYERS, OF YORK, PENNSYLVANIA.

AUTOMATIC RAILWAY-GATE.

SPECIFICATION forming part of Letters Patent No. 718,011, dated January 6, 1903.

Application filed February 28, 1902. Serial No. 96,119. (No model.)

To all whom it may concern:

Be it known that I, CHARLES E. MICKLEY, a citizen of the United States, residing at York, in the county of York and State of Pennsylvania, have invented a new and useful Automatic Railway-Gate, of which the following is a specification.

This invention relates to railway-gates, and has for its object to provide an improved train-actuated apparatus for controlling the swinging gate members at a crossing, so as to close the gate before the train reaches the crossing and to open the gate after the train has passed the crossing. It is furthermore designed to mount the controlling apparatus entirely independent of the rails of the track, so as to obviate weakening the rails by the formation of openings therein, and at the same time to provide a strong and durable mounting for operating parts, so as to obviate breakage and looseness thereof.

Another object is to arrange the wheel-engaging trip devices so as to gradually apply movement to the gate-arms and thereby avoid damage to the latter and the operating connections by reason of sudden jerks or jars.

A further object is to have all of the operating connections between the trip devices and the gate-arms below the surface of the earth, so as to be effectually housed and out of the way of vehicles and the like, and also to dispense with slots or openings in the surface of the ground, which are objectionable in that obstructions are liable to drop through such openings and interfere with the proper working of the controlling apparatus.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a railway-gate mounted at a crossing and constructed and arranged in accordance with the present invention. Fig. 2 is a longi-

tudinal sectional view thereof, taken at the outer side of the track in the plane of the gate-posts and through the pits which receive the crank-arms. Fig. 3 is a detail sectional view taken on the line 3-3 of Fig. 5 and through a pair of trip rock-bars to show the mounting thereof and to illustrate the relative position of a pair of successive trip projections. Fig. 4 is a detail perspective view of one of the trip rock-bars. Fig. 5 is a detail cross-sectional view taken through one of the rails of the track to show the relation thereto of one of the trip projections.

Like characters of reference designate corresponding parts in all the figures of the drawings.

In Fig. 1 of the drawings there has been shown a double track and a crossing of the ordinary type for the purpose of fully illustrating the application and operation of the improved gate. At one side of the crossing and at opposite sides of the railway-track there are provided the upstanding tubular posts 1 and 2, and similar posts 3 and 4 are provided at the opposite side of the crossing. The upper end of each post is open and provided at its rear side with a longitudinal slot, at each side of which is a perforate ear 5. Each post is provided with a vertically-swinging gate-arm 6, which is provided intermediate of its ends and near its lower and outer end with a laterally-projected bracket 7, the outer portion of which is received within the top of the post and is pivotally connected to the ears thereof by a suitable pivotal connection 8, whereby the arm is capable of swinging in a vertical direction. The lower and outer end of the gate is weighted—as, for instance, by metallic plates 9, fastened to opposite sides of the arm, so as to balance the same and insure a smooth and easy movement therefor. At the inner and upper end of each arm is a suitable swinging prop 10, which is loosely connected to the arm and is adapted to rest upon the ground and support the arm in its horizontal position. Although I have shown two arms at each side of the track, it will of course be understood that one long arm may be employed in lieu of two short arms whenever such an arrangement may be desirable.

For controlling the gate-arms by the passage of a train a pair of rock-bars 11 and 12 are mounted transversely of the track at opposite sides of the crossing and at a suitable 5 distance therefrom—as, for instance, about two hundred yards—and in any event at such a distance as to insure a proper closing of the gate before the locomotive reaches the crossing and to prevent opening of the gate before 10 the rear end of the train has passed over the crossing. Each rock-bar extends entirely across the two tracks and is mounted in a longitudinal groove or recess 13, formed in the bottom of one of the ties 14 and held in 15 place by means of the plate 15, secured to the bottom of the tie. By this arrangement it will be observed that the rock-bar is not mounted upon the rails, and therefore the latter are not weakened by the formation of openings 20 therein. A pair of trip projections 16 extend laterally outward toward the crossing and through vertically-disposed slots or openings 17, formed in the adjacent side of the tie, so as to permit of vertical rocking movements 25 of the projections, the latter being bowed upwardly, so that their beveled or pointed upper ends may lie just below the treads of the 30 rails and in the path of wheel-flanges, it being understood that each trip projection lies close to the inner side of the adjacent rail, and its inner side is provided with a lateral 35 head or extension 18, located at its upper end and projected toward the rail, so as to overlap the flange thereof and lie in the path of wheel-flanges, as best indicated in Fig. 5.

At each end of each rock-bar 11 there is provided a pendent crank-arm 19, which works in a pit 20, which is preferably walled up with masonry and is of a size just sufficient to permit the necessary movement of the arm 19. 40 The top of the pit is covered by a removable plate or cover 21, and the adjacent end of the tie 14 rests upon this plate. The other rock-bar 12 is provided with a long pendent crank-arm 22, which also works in a pit 23, which is entirely independent of the pit 20 and is provided with a cover-plate 24. A flexible 45 connection 25, either a wire cable, a rope, or a chain, has its opposite ends connected to the lower free ends of the crank-arms 19 and 22 and works through a hollow or tubular casing 26—as, for instance, a metal pipe—the opposite ends of which pierce the opposite walls of the two pits. By this arrangement 55 the pits may be comparatively small and at the same time the flexible connection is housed to prevent interference by obstructions. Another flexible connection 27 extends from the lower end of the longer and 60 inner crank-arm 22 and has its opposite end connected to the adjacent gate-arm, as indicated at 28, preferably to the bracket 7 and in advance of the pivotal support 8, the intermediate portion of the connection being 65 passed through a tube or housing 29, extending from the front wall of the pit 23 and piercing the lower end portion of the adja-

cent gate-post, there being a pulley or other suitable guide 30, mounted within the bottom portion of the post and over which the 70 connection 27 is reeved. It is thus apparent that the flexible connection between the crank-arms and the gate-arm is effectually housed throughout its entire length, and none of the parts are projected upwardly through 75 openings in the surface of the ground.

The connections just described are between one pair of crank-arms and the adjacent gate-arm, and it will of course be understood that duplicate connections are provided between 80 each pair of crank-arms and the respective gate-arms. Each inner and longer crank-arm is also in operative relation to the opposite gate-arm by means of a flexible connection 31, which passes through a tube 32, 85 piercing the inner wall of the pit 23 and the lower portion of the opposite gate-post, said connection passing around the pulley 30, which is a double pulley, so as to receive both of the connections 31 and 27, said connection 90 31 also extending upwardly through the tubular post and connected to the bracket 7 substantially at the point 28, where the connection 27 is fastened.

In the operation of the device when a train 95 approaches from either direction the wheel-flanges thereof strike the upper ends of the trip projections 16, whereby the rock-bar 11 is rocked to throw the opposite crank-arms 19 outwardly or away from the gate-posts, whereby the connection 25 is pulled and through the connections 27 and 31 the gate-arms are swung downwardly, so as to lie in horizontal positions, and thereby form obstructions or barriers extending across the crossing and at 105 opposite sides of the track. The projections 16 at the opposite side of the crossing will be held down by the wheel-flanges until the rear end of the train has passed the crossing, when they will be released, and the gate-arms 110 will return by gravity to their upright positions by reason of their weighted ends 9. It will here be observed that only one set of connections are in operation at a time, the opposite set remaining loose and having no operating effect whatever. 115

The purpose of having a pair of rock-bars is to increase the rate of movement applied to the gate-arms from the initial to the final movements thereof in the following manner: 120 As best indicated in Fig. 3, it will be seen that each trip projection 33 thereof is longer than the corresponding projection 16, and the relation of the lengths of these parts is such that the upper end of the projection 33 is still 125 in the path of wheel-flanges when the projection 16 has been forced to its lowermost limit by said flanges, whereby the wheel-flanges are adapted to also force the projection 33 downwardly, and thereby impart an additional rotation to the rock-bar 12. By this arrangement of parts the trip projections 16 impart a slight initial movement to the gate-arms and the projections 33 impart an additional move- 130

ment thereto, whereby the movement is applied gradually and there is not a sudden jar or jerk upon the gate-arms and the operating connections. Furthermore, the crank-arms 5 19 are comparatively short, so as to transfer a short movement from the rock-bar 11 to the gate members and the rock-bar 12, and the arms 22 are considerably longer, so as to give an increased rate of movement during the 10 latter stages of the movements of the gate-arms.

When the locomotive has passed over the crossing, its wheel-flanges will engage with the trip projections at the opposite side of 15 the crossing, and in view of the fact that the upper end portions of these trips are disposed in a vertical position they will be forced downwardly and turn the respective rock-bars so as to hold the gate-arms closed, and in view 20 of the fact that the projections are disposed so as to yield under pressure from either direction said projections are prevented from being broken by contact with wheel-flanges. As clearly indicated in Fig. 3, it will be observed 25 that the backs of the slots 17 form stops in the paths of the trip projections, so as to hold the latter in proper positions for effective engagement with wheel-flanges.

From the foregoing description it is apparent 30 that the present invention provides an exceedingly simple and effective means for automatically closing and opening railway-gates by the passage of a train, and all of the connections between the gate-arms and the 35 trips for engagement by wheel-flanges are located entirely below the surface of the ground, so as to obviate interference by external objects, and are also housed, so as to avoid interference by frosts, thaws, &c.

40 What I claim is—

1. The combination with the members of a railway-gate, of a vertically-swinging trip device mounted upon the under side of a tie and projected upwardly through an opening therein and into the path of wheel-flanges, and an operative connection between the trip device and the gate members.

2. The combination with the members of a railway-gate, of a cross-tie having a longitudinal groove formed in the bottom thereof, and also provided in one side with a vertical opening communicating with the groove, a rock-bar mounted in the groove and provided with a laterally and upwardly directed trip projection working in the opening and having its upper end projected above the top of the tie and lying in the path of wheel-flanges, and an operative connection between the rock-bar and the gate members.

60 3. The combination with a member of a railway-gate, of a rock-bar mounted upon the bottom of one of the cross-ties and provided with a trip projection carried by one side of the bar and projected upwardly at one side and above the top of the cross-tie and into the path of wheel-flanges, the tie having an opening in one side thereof to accommodate

the trip projection, and an operative connection between the rock-bar and the gate member.

70

4. The combination with a railway-track, having a pit formed at one end of one of the cross-ties thereof, and a swinging gate member, of a rock-bar mounted upon the under side of said cross-tie with one end projected over the pit, a trip projection carried by the rock-bar and normally lying in the path of wheel-flanges, a pendent crank-arm carried by the rock-bar and working in the pit, and an operative connection between the crank-arm and the gate member.

75

5. The combination, of a pair of posts at one side of a railway-track, gate members pivoted to the posts, guides upon the posts, train-operated trip mechanisms at opposite 85 sides of the gate and embodying a plurality of independent crank-arms, flexible connections between the crank-arms and the respective adjacent gate members, each connection having its intermediate portion working 90 through the guide upon the adjacent post with its opposite ends connected respectively to the gate member and the crank-arm, and an independent flexible connection between each crank-arm and the opposite gate member, with an intermediate portion working in 95 the guide of the opposite post, and its opposite ends connected respectively to the crank and said opposite gate member.

6. In a railway-gate, the combination of a 100 pair of tubular posts located at one side of the track, gate members pivoted upon the upper ends of the posts, guides within the lower portions of the posts, train-operated trip mechanisms located at opposite sides of 105 the gate and embodying crank-arms, a flexible connection between each crank-arm and the adjacent gate member, the intermediate portion of the flexible connection working in the post and through the guide, and an independent flexible connection between each 110 crank-arm and the opposite gate member, an intermediate portion of said flexible connection working in the opposite post and through the guide thereof.

115

7. In a railway-gate, the combination of a 120 pair of tubular posts located at one side thereof, swinging gate members mounted upon the posts, guides located within the lower portions of the posts, train-operated trip mechanisms located at opposite sides of the gate and embodying pendent crank-arms working in pits, a tubular casing extending between each pit and the adjacent tubular post, a flexible connection between each crank-arm and the adjacent gate member, the intermediate portion of said connection working in the post, through the guide thereof and through the tubular casing, another tubular casing 125 extending between each pit and the opposite post, and another flexible connection between each crank-arm and the opposite gate member, the intermediate portion of said connection working in the opposite post, through

130

the guide thereof and through the last-mentioned tubular casing.

8. The combination with the members of a railway-gate, a pair of rock-bars located one in advance of the other at one side of the gate, trip projections carried by the rock-bars and rising into the path of wheel-flanges, the top of the trip of the inner rock-bar normally lying above the top of the trip projection of the outer rock-bar, a crank-arm carried by the outer rock-bar, a longer crank-arm carried by the other rock-bar, an operative connection between the two crank-arms, and an operative connection between the free end of the longer crank-arm and the gate.

9. In a railway-gate, the combination of opposite tubular posts located at one side of the track, swinging gate members mounted upon the tops of the posts, guides within the bottom portions of the posts, a pair of rock-bars located at each side of the gate and mounted transversely beneath the rails, trip projections carried by the rock-bars and lying in the path of wheel-flanges, the top of the trip projection of the inner bar normally lying above the top of the trip projection of the outer bar, a pendent crank-arm carried

by the outer rock-bar and working in a pit, a longer crank-arm carried by the inner rock-bar and working in an independent pit, a tubular casing extending from one pit to the other, a flexible connection passing through the tubular casing and connected to the lower ends of the crank-arms, a tubular casing extending between the inner pit and the adjacent tubular post, a flexible connection passing through said casing, through the guide within the post and having its opposite ends connected to the long crank-arm and the adjacent gate, another tubular casing extending from the inner pit to the opposite tubular post, and a flexible connection working through said casing, through the guide in the opposite post, and having its opposite ends connected respectively to the opposite gate member and an intermediate portion of the longer crank-arm.

In testimony that I claim the foregoing as my own I have hereto affixed my signature in the presence of two witnesses.

CHARLES E. MICKLEY.
